(57) **CLAIM**

The ornamental design for a travel trailer, as shown and described.

DESCRIPTION

FIG. 1 is a front perspective view of the travel trailer, showing our new design;

FIG. 2 is a rear perspective view of the travel trailer;

FIG. 3 is a front view of the travel trailer;

FIG. 4 is a rear view of the travel trailer;

FIG. 5 is a right side view of the travel trailer;

FIG. 6 is left side view of the travel trailer; and,

FIG. 7 is top view of the travel trailer.

The broken lines in the drawings illustrate portions of the travel trailer that form no part of the claimed design.
